UNITED STATES PATENT OFFICE.

EDWIN D. MEAD, OF SHORTSVILLE, NEW YORK.

HAY AND GRAIN ELEVATOR AND CARRIER.

SPECIFICATION forming part of Letters Patent No. 320,267, dated June 16, 1885.

Application filed April 23, 1885. (No model.)

To all whom it may concern:

Be it known that I, EDWIN D. MEAD, of 5
Shortsville, in the county of Ontario and State
of New York, have invented certain new and
useful Improvements in Hay and Grain Ele-
vators and Carriers, of which the following is
a specification.

My invention relates to hay and grain elevators, carriers, and unloaders, and more 10
particularly to that class in which binding ropes or slings are used instead of forks, grapples, or like devices.

The present invention is designed as an improvement upon the apparatus for which Letters Patent were granted me on the 2d day 15
of December, 1884, numbered 308,621, and is designed to insure the proper and compact binding of the bundle, give increased power in elevating, and give the attendant perfect 20
control of the apparatus, so that at any point of elevation the car may be started and the bundle discharged.

Figure 1 is a perspective view of my improved apparatus. Fig. 2 is a top plan view of the car 25
with the carrying-rollers and their arms broken away; Fig. 3, a longitudinal vertical section through the car; Fig. 4, a vertical transverse section through the same on the line *x x* of Figs. 1 and 2; Fig. 5, a sectional 30
plan view of the hoisting-pulleys and their clutch mechanism; Figs. 6 and 7, elevations of the shirr-pulley block with the side partially broken away; Fig. 8, a horizontal section of 35
the same on the line *y y*, Fig. 7; Fig. 9, a detail view of the clutching mechanism.

In the practical use of this class of devices it is found that there is a tendency to lift the 40
load to the car or carrier before the binding ropes or slings are drawn tight, and when this happens the load is liable to escape from the 45
sling and fall before reaching the desired point. This shirr-pulley as commonly constructed has but a single rope, and the elevating devices do not afford sufficient power under all circumstances, and it is chiefly to overcome these 50
difficulties that the present invention is designed. This construction will be readily understood upon referring to the annexed drawings, in which—

55 A indicates a car or carrier; B, a pulley-block commonly called a "shirr-pulley block;" C, the hoisting-rope, and D the sling or binding-rope.

The car consists of two parallel slide-plates

or frames, *a a*, connected by bolts and held 55
apart by spacing-blocks, as usual, rollers *b*,
applied to the arms *c* of the side frames, hoist-
ing-pulleys, a pivoted frame carrying the
hoisting-pulleys, a lever connected with the
pivoted-frame and arranged to act in the man- 60
ner of a scale-beam, and a clutch mechanism
connected with and operated by the last-men-
tioned lever to connect the hoisting-pulleys
while binding the load, and to disconnect
them when the load is bound and is being ele- 65
vated. The construction and relation of these
parts may be best seen in Figs. 2, 3, 4, and 5.

E indicates a frame, pivoted at or near one
end to the car or carrier A by a cross-bolt, *d*,
which serves also as an axle for a guiding- 70
pulley, F. The frame E carries a cross-bolt
or rod, *e*, which forms an axle for pulleys G
and H, which pulleys are locked together
while the binding rope or sling is being drawn
tight about the load, but are separated and 75
allowed to rotate independently when the load
is being lifted, for which purpose said pulleys
G H are formed with teeth *f*, on their oppos-
ing faces, as best shown in Figs. 4 and 5.

I indicates a lever or beam, advisably fur-
nished with an adjustable weight, *g*, and piv-
oted near one end in frame *a a*, as shown in 80
Figs. 2 and 3, the weight being applied to the
long arm of the lever, and the shorter arm
thereof being connected by a link, *h*, to the 85
free end of the frame E, which carries the pul-
leys G H. Under this arrangement, and owing
to the great leverage it affords, the weight
g, or the lever I itself, if the weight be omit-
ted, serves to lift up the free end of the frame 90
E and to hold it up against a heavy weight or
force applied near the pivot of said frame.
The pulleys G H are located near the pivot *d*
of the frame E, and carry the hoisting-rope *c*,
which drawing down upon the pulleys G H 95
their frame E must overcome weight *g* and lever I
with all their advantage in leverage. It
will thus be seen that before the lever I can
be lifted a predetermined and very considera- 100
ble resistance must be offered by the load to
the hoisting or elevating power.

Lever I is connected by a link, J, with a
shifting-lever, K, hung or pivoted on the axle
e beside pulley G, which latter pulley is capa- 105
ble of being moved along the axle *e* to or from
pulley H, which latter is free to rotate on said
axle, but has no sliding movement thereon.
The shifting-lever K consists simply of an arm

perforated to fit the axle *e*, and provided with inclined lugs *i* on its outer face to ride upon like inclines, *j*, formed in or upon the pivoted frame *E*.

5 Owing to the connection of shifting-lever *K* and weight lever or beam *I*, and to the relative positions of the inclines *i* and *j*, it follows that when the lever *I* is down in its lowermost position the inclines ride upon each other and 10 force the shifting-lever inward against pulley *G*, thereby crowding said pulley *G* over toward pulley *H*, and causing the teeth *f* of the two pulleys to interlock. When this occurs the two pulleys must move together as one 15 double pulley.

When the load placed upon the hoisting-rope overcomes the leverage of frame *E* and beam or lever *I*, together with weight *g*, if used, the shifting-lever is actuated in the reverse direction, the inclines *i* and *j* ride back, allow the lever and the pulley *G* to be thrown outward by the inclined faces of the teeth *f* acting together with the guide-pulley, which sets to one side of the line of draft, and thus 25 the pulleys *G* and *H* are disconnected. Thus, it will be seen, the pulleys *G* and *H* are automatically locked together until the load or resistance reaches a certain predetermined point, at which point they are automatically 30 unclutched and allowed to rotate independently. The object and importance of this construction will appear farther on.

As shown in Figs. 2, 4, and 5, the pulleys *G* *H* are each made with a V-groove, and the 35 sides of the grooves are ribbed, this form being adopted to prevent the hoisting-rope from slipping on the pulleys. To still further guard against such slipping, the pulley *F* is provided with ribs and made of like form, the hoisting-rope being carried beneath said pulley and thereby made to wrap or be wound about the pulley *G* farther and more closely than if carried directly to the guiding-pulley *F*, and said pulleys *G* and *F* being provided with interlocking teeth, so that the rope cannot slip unless it loses its hold on both pulleys at the 45 same time.

To permit the draft-rope, which is merely a continuation of hoisting-rope *C*, to be carried beneath the car *A* toward either end of the track without interfering with the vertical rope, the guide-pulley *L* is placed at one side of the frame, as shown in Figs. 1 and 2.

M indicates a vertically-sliding frame or yoke the side bars of which are seated and move in grooves or guides *k* in the side frames, *a a*, of the car. The top bar or cross-piece of the yoke projects over and rests upon the side frames, *a a*, when at its lowest point. The 55 lower end of the yoke *M* is furnished with an inwardly-turned arm, *l*, having a hole or eye, *m*, through which passes a rod, *N*, pivoted at one end in the car *A*. To the free end of the rod *N* is attached a cord or rope, *O*, which 60 passes over a pulley, *n*, in the beam or lever *I*, and descends then to the floor of the barn or other structure in which the car is used.

When the rope is pulled, it raises rod *N* and with it the yoke or frame *M*, and the same elevation of the yoke or frame will occur whenever the pulley-block *B* is drawn up against its lower end. The purpose of this yoke is to raise the pivoted hooks *P*, which are applied to the sides of the track-beam or rail *Q*, and engage over blocks or lugs *o* formed upon the 75 arms *c*, as indicated by dotted lines in Fig. 1, to hold the car stationary while the load is being elevated. The hooks have their free ends bent upward, and are limited as to their descent, so that the lugs *o* ride freely under and 80 lift them when the car comes to its loading position. The hooks have their free ends turned in opposite directions, so as to lock the car against movement in either direction.

Referring now to Figs. 1, 6, 7, and 8, the 85 construction of the pulley-block *B* will be explained. As shown in several figures, this block is formed with a metal body or shell, *p*, the lower end of which is fashioned into a nose or horn, *q*, and provided with a spring latch or hook, *r*. 90 This construction is for the purpose of permitting the rings or eyes *s* of the compressing rope or sling *D* to be slipped over or upon the horn and held there by the latch or hook *r* until the latter is tripped or withdrawn, as is 95 now done with other devices of similar construction. The other end of the sling or compressing rope *D* is attached to the hoisting-rope *C*, which passes up through the pulley-block *B* to the car *A*.

R and *S* indicate two pulleys, mounted upon a bolt or axle, *t*, passing transversely through the shell or body *p*, as shown in Figs. 1 and 8. These pulleys are formed with teeth *u* on their opposing side faces, and adapted to be locked together or thrown apart in the same manner as the pulleys *G* *H* of the car *A*, and a shifting-lever, *T*, provided with inclines *v* to ride upon inclines *w* of the shell *p*, is mounted upon the axle *t*, as with said pulleys *G* *H*. When the shifting-lever *T* is lowered, the inclines crowd pulley *R* over against pulley *S*, causing their teeth *u* to interlock and the two pulleys to turn together as one double pulley; but when it is raised the pulleys are permitted to 110 separate and to rotate independently.

A push-bar, *U*, is jointed or attached to the outer end of shifting-lever *T*, and is also connected by a link, *x*, with the shell or body *P* of pulley-block *B*, in position to be struck and moved by the load when drawn up to the pulley-block, and as the load is only drawn against the push-bar as the binding or compressing is completed it follows that the pulleys will remain locked together during the binding operation and until the moment the hoisting begins.

The hoisting-rope, to which is attached one end of the compressing-rope, passes into pulley-block *B* below, goes up behind pulley *S*, thence through the upper end of the block to pulley *H* of the car, over said pulley and down to pulley *R* of the block *B*, thence up to and over pulley *G* of the car, thence under pulley

F and over pulley L to the pulley at the end of the track, and thence to the ground-pulley, beneath which the rope usually passes before reaching the horse.

5 V indicates a swinging or pivoted frame pivoted in the block B, and carrying a roller, y, at its forward or center side, behind which roller the sling or the draft-rope passes as the load is bound or compressed, the rope thus exerting an outward pressure upon the roll and tending to rock or tip said frame outward. The upper end of the frame is furnished with teeth z, which mesh with similar teeth z on the pulley R when the frame is tipped slightly 15 forward, and it is further formed with a dog or nose, a', which is shaped to enter the groove of pulley R and to bear against the rope therein. When the rope is being drawn up through the pulley-block B, the pulley R rotates in such 20 direction that it tends to throw the frame V inward and hold dog a' away from the rope; but whenever the rope begins to descend it turns pulley R in the opposite direction and tends to swing frame V outward and to bring 25 the nose or dog a' against the rope, thereby locking the same against accidental or premature descent.

The frame D carries at its inner side a roller, c', over which passes a cord or rope, d', one end 30 of which is attached to the spring-latch r. The other end after passing over roller c' drops to the floor or ground, where it may be reached by the attendant. By drawing up the rope or cord d' the latch r is tipped or withdrawn, 35 thereby allowing the eyes or rings s of the sling to escape from the horn q of the pulley-block B, and the frame V is swung inward upon its pivot and caused to release the hoisting or binding rope, which will allow the block B 40 to descend.

The apparatus being thus constructed, it is operated as follows: The block B is suspended from the car A by the hoisting-rope, the sling or binding-rope D being drawn down through 45 the block. A sling or binding-rope is laid lengthwise of the wagon and a quantity of hay or grain placed thereupon, a second rope and another bundle or layer of grain, and so on until the wagon is loaded. When it is desired to remove a load or layer from the wagon, 50 the shirr-pulley block is drawn down and the ring or rings s, at opposite ends of the top sling or rope, are slipped upon the horn q to a point above trip or latch r. A horse is 55 hitched to the draft-rope, which, as before stated, is a continuation of the hoisting-rope, and said rope running around pulleys L, F, and G draws upward on the hoisting-rope, which passes around pulley R of block B, 60 back over pulley H of car A, and finally down through block B, and behind pulley S thereof, to the binding rope or sling, which is thus caused to draw firmly around the load and to bind it tight. While this is being 65 done the pulleys G H of the car and the pulleys R S of the block are locked together, as explained, and thus the hoisting-rope is caused

to pass up on one side and down on the other equally, and hence no lifting action is exerted on the block. When, however, the load is 70 firmly drawn up or bound by the sling D, the load acts against push-bar, moves shifting-lever T, and permits the pulleys R S to separate, and as the sling and hoisting-rope can move no farther through the block the latter 75 begins to rise. As the weight of the load thus comes upon the pulleys G H and their supporting-frame E, the movable end of said frame is depressed, thereby throwing up the weighted end of beam or lever I and rocking 80 the shifting-lever K, which permits the pulleys G H to unlock and to rotate separately, thus giving the greater power of two independent pulleys acting in connection with the third pulley, R, of block B, and giving ample 85 power for hoisting the load. When the block B is raised close to the car, it strikes and raises the yoke M, lifts the hooks P, and allows the car to be drawn to the required point. When there, the cord or rope d' is pulled by 90 the attendant below, the latch r is withdrawn, the rings s are permitted to escape from horn q, and thus the load is discharged. The beam or lever I and the push-bar then fall by gravity and cause the pulleys G H of the car and 95 the pulleys R S of the block to lock together in pairs, as mentioned, the draft-rope and the car are carried back, and the block descends for a fresh load.

The beam I and sliding yoke M, with rod 100 N, may be furnished with a shifting rope or bar by which to depress beam I, actuate the shifting-lever, K, and raise yoke M; or the frame E and lever I may be dispensed with altogether by hanging the pulleys G H and 105 shifting-lever K directly in the car A, and changing the pulley from beam I to the shifting-lever K for the shifting-rope and operate it altogether by hand.

Having thus described my invention, what 110 I claim is—

1. In a car or carrier for hay and grain elevators and unloaders, the combination of two pulleys provided with teeth upon their opposite side faces, and a lever adapted to force the pulleys together or to permit them to separate at will, whereby the pulleys may be caused to rotate together as one pulley or to rotate independently and at different speeds to give additional power when hoisting. 115

2. In a car or carrier for elevating and unloading hay, &c., the combination of a main body, a frame pivoted therein and provided with two pulleys adapted to be clutched and unclutched to and from each other, a shifting-lever adapted to clutch and unclutch said pulleys, and a beam or lever connected with the pivoted frame and with the shifting-lever substantially as shown and described, whereby the frame is held up and the pulleys are locked together until a predetermined weight or strain is brought upon the pulleys, and then the frame is caused to descend, raise the beam or lever, and unclutch the pulleys. 125 130

3. The combination of a car provided with a vertically-movable frame, pulleys mounted in said frame and adapted to be locked together or disconnected, a shifting-lever for connecting and disconnecting said pulleys, a beam or lever connected with the vertically-movable frame and with the shifting-lever, and a pulley-block suspended from the car by a rope passing about the pulleys of the car and pulley-block, substantially as shown. 5
4. In combination with a car provided with pulleys adapted to be coupled or uncoupled, and a shifting-lever for controlling said pulleys, a pulley-block provided with pulleys adapted to be coupled and uncoupled, and with a shifting-lever for effecting the coupling and uncoupling of said pulleys, and a rope passing about the pulleys of the car and block, substantially as described and shown. 15
- 20 5. The combination, substantially as set forth, of a car provided with a movable frame, pulleys carried by said frame and adapted to be coupled and uncoupled, a shifting-lever for said pulleys, and a beam connected with the frame and shifting-lever and adapted to be moved by variation of the weight brought upon the pulleys, a pulley-block provided with pulleys adapted to be coupled and uncoupled, a shifting-lever for controlling said pulleys, a push-bar connected with said lever and adapted to be moved by the load as the latter is drawn up to the block, a hoisting-rope passing about the pulleys of the car and block, and a sling or binding-rope attached at one end to the hoisting-rope and at its other end to the pulley-block, whereby the hoisting-rope is caused to move through the car and block equally while the load is being bound or compressed, and then to cease its travel through the block and to have the power of all the pulleys acting independently in lifting the load. 35
- 40 6. In a car or carrier for hoisting, moving, and discharging hay and grain, the combination of body *a*, frame *E*, pivoted therein, axle *e*, carried in said pivoted frame, pulleys *G H*, mounted upon said axle and formed with teeth *f*, shifting-lever *K*, and pivoted beam *I*, connected with frame *E* and shifting-lever *K*, substantially as described and shown. 45
- 50 7. The combination, in a car or carrier, of a main body, frame *E*, pivoted therein, and provided with axle *e*, pulleys *G H*, mounted on said axle and provided with teeth *f*, shifting-lever *K*, lever *I*, connected with frame *E* and lever *K*, and guide-pulley *F*, gearing with pulley *G*, for the purpose explained. 55
- 60 8. In combination with a car or carrier substantially such as described and shown, a guide-pulley mounted therein at one side of the hoisting-rope pulleys, whereby the draft end of the hoisting-rope may be carried beneath the car toward either end thereof without interfering with the hoisting-rope. 65
9. In combination with track *Q*, provided with hooks *P*, car *A*, provided with yoke *M*, rod *N*, pulley *n*, and rope *O*. 70
10. In combination with track *Q*, provided with hooks *P*, car *A*, provided with yoke *M*, pulley-block *B*, and hoisting-rope *C*. 75
11. In a hoisting apparatus, a pulley-block provided with two pulleys adapted to be locked together or released at will, whereby a single or double purchase may be had without changing the arrangement of the hoisting-ropes. 80
12. In a hoisting apparatus, a pulley-block provided with shell *p*, having inclines *w*, pulleys *R S*, having teeth *u*, and lever *T*, provided with inclines *v*, substantially as and for the purpose set forth. 85
13. In a hoisting apparatus, a pulley-block having its shell *p* provided with inclines *w*, pulleys *R S*, provided with teeth *u*, lever *T*, provided with inclines *v*, and push-bar *U*, connected with the lever *T* and extending below the lever to be struck and moved by the load. 90
14. The combination, in a pulley-block, of a pulley having gear-teeth, and a movable frame provided with corresponding teeth and with a nose or dog to enter the groove of the pulley, whereby a rope is permitted to pass freely over the pulley in one direction, but is clamped and held by the dog against movement in the opposite direction. 95
15. In combination with shell *p* and pulley *R*, movable frame *V*, said pulley and movable frame being both provided with teeth *z*, and the frame provided with nose or dog *a'*, substantially as and for the purpose set forth. 100
16. In combination with shell *p*, pulley *R*, and frame *V*, said frame and pulley both provided with teeth *z*, and the frame being further provided with dog *a'*, cord *d'* for drawing back the frame *V*. 105
17. In combination with shell *p*, having nose or horn *q* and latch *r*, pulley *R*, and frame *V*, both provided with teeth *z*, and the latter provided with dog *a'* and roller *c'*, and cord *d'*, attached to latch *r*, passing over roller *c'* and through shell *p*, substantially as and for the purpose explained. 110
18. In a hoisting apparatus, the herein-described pulley-block, consisting of shell *p*, provided with inclines *w*, pulleys *R S*, provided with teeth *u*, lever *T*, having inclines *v*, push-bar *U*, frame *V*, provided with teeth *z* to mesh with like teeth on pulley *R*, and having dog *a'* and roller *c'*, and cord *d'*, all substantially as described and shown. 115
19. The combination, in a car or carrier provided with pulleys *G H*, and shifting-lever *K*, of a guide-pulley, *F*, gearing with pulley *G*, for the purpose explained. 120
20. The combination of a car provided with pulleys mounted therein and adapted to be locked together or disconnected, a shifting-lever for connecting and disconnecting said pulleys, and a pulley-block suspended from the car by a rope passing about the pulleys of the car and pulley-block, substantially as shown. 125
